154,851

DESIGN FOR A FLOOR SANDER

William P. Hilger, St. Cloud, Minn.

Application January 29, 1948, Serial No. 144,139

Term of patent 7 years

(Cl. D9—2)

To all whom it may concern:

Be it known that I, William P. Hilger, a citizen of the United States, residing at Saint Cloud, in the county of Stearns and State of Minnesota, have invented a new, original, and ornamental Design for a Floor Sander, of which the following is a specification, reference being had to the accompanying drawing, forming a part thereof.

Fig. 1 is a top plan view of a floor sander showing my new design;

Fig. 2 is a side elevational view thereof;

Fig. 3 is a front end view thereof; and,

Fig. 4 is a rear end view thereof.

I claim:

The ornamental design for a floor sander, as shown.

WILLIAM P. HILGER,
